HAIRBRUSH OR SIMILAR ARTICLE

Rene X. Gibo, Frederick, Md., assignor to Ox
Fibre Brush Company, Inc., Frederick, Md.

Application January 2, 1951, Serial No. 13,649

Term of patent 14 years

(Cl. D86—10)

To all whom it may concern:

Be it known that I, Rene X. Gibo, a citizen of the United States of America, residing at Frederick, county of Frederick, and State of Maryland, have invented a new, original, and ornamental Design for a Hairbrush or Similar Article, of which the following is a specification, reference being had to the accompanying drawing, forming a part thereof, wherein:

Figure 1 is a view in side elevation of a hairbrush or similar article, showing my new design;

Figure 4 is a sectional view taken on the plan indicated by the line 4—4 of Figure 1, looking in the direction indicated by the arrows.

I claim:

The ornamental design for a hairbrush or similar article, as shown.

RENE X. GIBO.
